A technical drawing of a device. It features two cylindrical components, each with a central hole, labeled '20'. A rectangular base plate is labeled '19'. To the right of the drawing is a handwritten signature 'W.W. Harris,' with the word 'Inventor' written above it in a smaller, cursive font.

UNITED STATES PATENT OFFICE.

WALTER W. HARRIS, OF BROWNSBURG, PENNSYLVANIA.

CURRYCOME.

1,137,613.

Specification of Letters Patent. Patented Apr. 27, 1915.

Application filed April 26, 1911. Serial No. 623,412.

To all whom it may concern:

Be it known that I, WALTER W. HARRIS, a citizen of the United States, residing at Brownsburg, in the county of Bucks and State of Pennsylvania, have invented certain new and useful Improvements in Currycombs, of which the following is a specification.

My invention relates to improvements in curry combs, and has for its leading object the provision of an improved simple and inexpensive curry comb which may be quickly and readily cleaned.

A further object of my invention is the provision of an improved curry comb having separable teeth, and having means secured to said teeth for shifting the teeth with respect to the main or base plate of the curry comb, whereby the teeth may be quickly shifted from normal position to cause them to rub against the main plate and scrape the hair or other material thereon off and may be readily moved into their former operative position.

Other objects and advantages of my improved curry comb will be apparent from the following description taken in connection with the accompanying drawings, and it will be understood that I may make any modifications in the specific structure shown and described within the scope of the claims without departing from or exceeding the spirit of the invention.

Figure 1 represents a top plan view of my complete curry comb, Fig. 2 represents a side elevation thereof, Fig. 3 represents a longitudinal sectional view of the curry comb in operative position, Fig. 4 represents a similar view with the teeth in cleaning or raised position, Fig. 5 represents a perspective view of the pivot post carried by the base plate, and Fig. 6 represents a perspective view of the trip and post showing the use of a coil spring in connection therewith.

In the drawings, the numeral 1 designates the wooden handle of my curry comb, in which is secured the rod 2 having the furcations 3 at its outer end, said furcations 3 being secured to the reduced end 4 of the main or base plate 5 of my curry comb. Said plate 5 has the plurality of transversely disposed slots 6 formed therein, while the portion of the plate adjacent each of the slots is stamped or pressed downward to provide the converging edges 7.

Passing through the slots 6 are the arms 8 of the U-shaped plates 9, said arms passing through pairs of adjacent slots and having formed on their lower edges the serrations or comb teeth 10. The plates 9 have secured thereto the bracing plates 11, said plates extending longitudinally of the curry comb and having secured centrally thereto the curved plate springs 14 rounded or reversely curved at 12 and bearing against the bracket members 13 and sliding therealong. The springs 14 thus tend to force the teeth downward into operative position through the slots 6 of the frame plate. To brace the plates 9 and further to aid in said upward forcing of the same, I secure to their bases or portions connecting the two arms 8, the base flanges 16 of the pair of parallel L-plates 17 which have the slots 18 formed therein intermediate their length. Secured to the portion 4 of the plate 5 is the casting 19 having the upstanding posts 20, while secured to said posts 20 by the pivot 21 is one end of the curved arm 22 which bears on its free end the cross bar or double pintle 23 which is slidably engaged in the slots 18 of the plates 17. Formed integral with the curved arm 22 and projecting therefrom is the arm 24 terminating in the knob 25, said knob being disposed adjacent the end of the handle 1. To aid the spring 14 in yieldingly resisting the upward movement of the teeth, I secure to the casting 19 either the blade spring 26 or the coil spring 27, the other end of the spring 26 or 27 engaging one of the arms of the trip to resist the pivotal movement of said arms and thus the movement of the teeth.

From the foregoing description taken in connection with the drawings, the construction of my improved curry comb will be readily understood, and it will be seen that I have provided a simple, inexpensive, durable and efficient curry comb in which the teeth may be easily raised through slots in the main plate, said main plate having the edges of the slots so disposed with respect to the teeth as to scrape or clean the hair or other matter from the teeth of the comb, and it will further be observed that I have provided improved resilient means for yieldingly holding the teeth in operative position and for shifting the teeth into cleaning position.

I claim:

1. A curry comb comprising a plate hav-

ing transverse slots formed therein, a handle for the plate, U-shaped comb teeth operable in the slots, the bight portions of which normally engage the upper surface of the plate, 5 longitudinal bracing plates connecting the bights of said teeth, bars connecting the comb plates and having slots formed intermediate their ends, a pair of spaced brackets secured at their opposite ends to the plate 10 and embracing the bights of the comb teeth, bowed springs disposed between the brackets and comb teeth and rigidly connected to the bracing strips to normally hold the teeth extended from the plate, a bell crank lever 15 mounted on the plate adjacent the handle and having one of its arms located between the bars and provided with a cross bar adapted to slidably engage said slots, said bell crank lever being rocked upon pressure 20 being applied to its other arm by the user's hand without disengaging the handle, whereby the bights of the comb teeth are forced out of contact with the plate and against the tension of the bowed springs and 25 a spring connecting the bell crank and plate, as and for the purpose set forth.

2. A curry comb comprising a flat plate having transversely extending slots, elongated inverted U-shaped members mounted on said plate and having the legs thereof extending downwardly through the slots and slidably therein, parallel strips connecting said U-shaped members above the plate, said strips having parallel elongated slots therein, a brace member connected to the plate 30 and extending over the strips, a bowed spring connected to one of the strips and pressing against the brace to normally maintain the aforementioned legs in their lowermost positions and a lever slidably connected to the said strips, a handle connected to the plate, said lever being pivoted to the handle and arranged to raise the aforementioned legs so that the lowermost edges thereof will lie substantially in the plane of 40 the plate.

In testimony whereof I affix my signature, in the presence of two witnesses.

WALTER W. HARRIS.
